CLAIM

The ornamental design of a charger for a hand-held mixer, as shown and described.

DESCRIPTION

FIG. 1 is a bottom plan view of a charger for a hand-held mixer showing my new design;

FIG. 2 is a front elevational view thereof;

FIG. 3 is a left side elevational view thereof;

FIG. 4 is a top plan view thereof;

FIG. 5 is rear elevational view thereof;

FIG. 6 is a right side elevational view thereof; and

FIG. 7 is a top, front and left side perspective view thereof.

The electric cord is shown broken away in FIGS. 1-5 and 7 for ease of illustration and is understood to represent indeterminate length.
